UNITED STATES PATENT OFFICE

HENRY THOMAS, OF RIDLEY PARK, PENNSYLVANIA, ASSIGNOR TO SUN OIL COMPANY,
OF PHILADELPHIA, PENNSYLVANIA, A CORPORATION OF NEW JERSEY

TUBE STILL FURNACE

Application filed July 28, 1928. Serial No. 296,051.

My invention relates to tube still furnaces. Such furnaces comprise fire-brick walls enclosing banks of tube-sections through which circulates oil that is heated by means of hot gases that flow between and around the tubes and transfer thereto and to the flowing stream of oil more or less of their heat.

The furnace to which my invention has been applied comprises one or more "Dutch ovens" communicating with a single, long, upright gas-combining and oil heating chamber. The invention is applicable to any heating chamber in which are arranged banks of tubes superimposed one upon another. The oil or other liquid to be heated and thereby distilled, cracked or otherwise treated flows through the tube banks successively, usually from bottom to top but permissively in the opposite direction, and the hot gases flow through the chamber into heat exchange relation with the tubes, usually upwardly, but permissively downwardly. The several tube banks may be arranged in series or in multiple. Usually they comprise one long continuous conduit, which is divided into "banks" as a matter of nomenclature, because it is desirable to support tubes at different levels in different ways. In illustrating the invention, only the combustion chamber and the contained tubes and their supporting means are shown, as the whole invention is comprised therein.

In an application filed by me July 6, 1927, Serial No. 203,702, a tube still of the character described is set forth. Therein are disclosed beams overlying the chamber, bars extending within and transversely of the chamber and supporting an upper bank of tubes, and hangers depending from the overlying cross-beams and supporting the bars. Therein are also disclosed cross-beams overlying the chamber, hangers depending from said cross-beams, other cross-beams within the chamber supported by said hangers, hangers depending from said inside cross-beams, and bars extending within and transversely of the chamber and supported by the last-named hangers; the bars supporting a lower bank of tubes.

The above tube-supporting means is admi-

rably adapted to a fair sized tube still. In a large tube still, however, it is advisable to divide the tubes into three or more banks. It is practicable to support the upper bank of tubes and one of the lower banks, preferably the lowest, as above described. But in the case of a large tube still, it has been found necessary to provide modifications of and additions to the tube-supporting means shown in my said application. These modifications and additions comprise the present invention.

Where the furnace is of large dimensions it is impracticable, or at least undesirable, to support the internal cross-beam solely from an overhead cross-beam, but it is desirable to so support it in part. If, however, such internal cross-beam is located a substantial distance from the top of the combustion chamber, the longitudinal expansion and contraction of the supporting hanger or hangers are such as to make this method of support apparently impracticable. Either, due to expansion of the hanger, the internal cross-beam will sag very much, or it will be forced to carry the entire load without the aid of such hanger or hangers.

One of the objects of the present invention is to provide for supporting the internal cross-beam in part or in whole from overhead cross-beams regardless of the degree of expansion or contraction of such hanger or hangers.

Another object of the invention is to provide special means for supporting a middle bank of tubes from such cross-beam.

A preferred embodiment of the invention is shown in the drawings, in which:

Fig. 1 is a cross-sectional elevation through the still.

Fig. 2 is a longitudinal sectional elevation.

Fig. 3 is a plan view.

The fire-brick walls *a* enclosing the heating chamber, or tube-containing space of the furnace, rest on horizontally extending I-beams *c* which are in turn supported on short columns *c'*. The roof *b* of the furnace is supported on the walls *a* in any desired way.

Outside the walls *a* of the furnace are erected tall columns *d*, on which rest, above the roof level, transversely extending end

beams or girders *e* and one or more transversely extending intermediate beams or girders *f*. Carried between adjacent cross girders along each side are longitudinally extending I-beams *g*. Supported on, and extending over, longitudinally extending I-beams *g* are cross girders *h*.

Depending from cross-beams *f* are rods *i*, which are jointed so that their lower ends 10 form links. From these links are suspended cross-bars, from which depend short links which support lower cross-bars, from which depend other links which support still lower cross-bars, and so on. The cross-bars are 15 lettered *j* and the links *k* and are more fully described in my said prior application. The upper bank *x* of tubes is supported on these cross-bars *j*.

Extending across the furnace, between the 20 middle bank *y* of tubes and the lower bank *z* of tubes are girders *m* and *n*, directly beneath and parallel with girders *f* and *h*. These girders extend through the side walls 25 of the furnace and their ends are supported on longitudinally extending I-beams *g*', which are carried between columns *d*.

From each cross girder *m* depend hangers *o*, which suspend cross-bars, from which depend links which support lower cross-bars, 30 from which depend links which support still lower cross-bars, and so on. The cross-bars are lettered *p* and the links *r* and are more fully described in my said prior application. The lower bank *z* of tubes is supported on 35 these cross-bars *p*.

Resting on each cross girder *n* are a lower tier of I-bars. By means of pairs of plates *t* (the plates of a pair being bolted together at *u*), the lower tier of I-bars supports a higher 40 tier of I-bars, which, in turn, by means of similar pairs of plates, supports a still higher tier of I-bars. On these I-bars, which are lettered *v*, rest the middle bank *y* of tubes.

The lower bank of tubes is thus carried by 45 suspension members, which in turn are carried by the large girders *m*, while the middle bank of tubes is carried by compression members, which in turn are carried by the large girders *n*; both girders *m* and *n* being positioned between the lower and middle groups 50 of tubes.

In view of the weight and length of girders *m* and *n*, it is highly desirable to support them between their ends. As heretofore explained, 55 it is impracticable, because of their great contraction and expansion, to support them from hangers secured directly to girders *f* and *h*. In order that these girders *m* and *n* shall be effectively supported between their ends at 60 all times irrespective of temperature conditions the following mode of suspension has been found practicable.

Supported on each girder *h* are pairs of standards 10, 10. On the standards of each 65 pair are pivoted, between their ends, levers 11,

11, the inner short arms of which are jointed to a hanger link 14, while their outer longer arms carry weights 13. Link 14 extends down between the beams of girder *h* through the roof of the furnace and between the beams of girder *n* and has secured to its lower end a member 15, on which girder *n* rests. Thereby a uniform tension is maintained on this link at all times, regardless of temperature conditions.

Each girder *m* is supported between its ends 70 from girders *f* by means of a similar link 20, the upper end of which is similarly supported by means of weighted levers 21.

In specifying in the claims that the hanger 80 supports the central portion of the beam *n*, I do not desire to be restricted to the engagement of the hanger with the beam precisely midway between the ends of the beam, so long as it is located substantially nearer the 85 center than the ends and is thus adapted to support the central portion.

What I claim and desire to protect by Letters Patent is:

1. A furnace comprising walls and a roof 90 enclosing a heating chamber, tubes therein, a lower tube-supporting beam extending within and transversely of the chamber and supported against vertical movement at its ends, an overhead beam, a hanger extending from said overhead beam and supporting the central portion of said lower beam and means, carried by said overhead beam, adapted to movably support the upper end of said hanger and maintain a tension thereon to 95 provide for longitudinal expansion and contraction of the hanger, thereby transmitting a uniform load to, and thus substantially preventing sagging of, the lower beam.

2. A furnace comprising walls and a roof 100 enclosing a heating chamber, tubes therein, a lower tube-supporting beam extending within and transversely of the chamber and through its side walls, means, outside the chamber, supporting the ends of said beam, 110 an overhead beam, a hanger extending from said overhead beam and supporting said lower beam between its ends, and means, carried by said overhead beam, adapted to movably support the upper end of said hanger 115 and maintain a tension thereon notwithstanding its longitudinal contraction and expansion.

3. A furnace comprising walls and a roof 120 enclosing a heating chamber, tubes therein, a lower tube-supporting beam extending within and transversely of the chamber and supported against vertical movement at its ends, an overhead beam, a hanger extending from said overhead beam and supporting the central portion of said lower beam, and a weighted lever supported by said overhead beam and connected in supporting relation with the hanger, said weighted lever thus 125 transmitting a uniform load to, and substan- 130

tially preventing sagging of, the lower beam notwithstanding longitudinal expansion and contraction of the hanger under changing temperature conditions.

5 4. A furnace comprising walls and a roof enclosing a heating chamber, tubes therein, a lower tube-supporting beam extending within and transversely of the chamber and supported against vertical movement at its 10 ends, an overhead beam, a hanger extending from said overhead beam and supporting the central portion of said lower beam, a pair of standards supported on said overhead beam on opposite sides of the upper end 15 of the hanger, and weighted levers on opposite sides of the upper end of the hanger and pivoted on the respective standards and in supporting connection with the hanger, said weighted levers equalizing the side pull 20 on the hanger and transmitting a uniform load to, and substantially preventing sagging of, the lower beam notwithstanding contraction and expansion of the hanger.

5 5. A furnace comprising walls and a roof 25 enclosing a heating chamber, beams extending transversely within the chamber, tiers of tube-supporting bars extending transversely within the chamber below said beams, hangers by means of which said tiers of bars are 30 supported, one below another, from one of said beams, tiers of tube-supporting bars extending transversely within the chamber above said beams, and supports by means of which the last named tiers of bars are 35 supported, one above another, from the other of said beams.

6. The construction set forth in claim 5 and comprising also overhead beams extending above the furnace roof, and hangers supported from said overhead beams and extending downward through said roof and supporting the inside tube-supporting beams between their ends.

7. A furnace comprising walls and a roof 45 enclosing a heating chamber, a beam of relatively large cross-section extending transversely within the chamber, tiers of tube-supporting bars of relatively small cross-section extending transversely within the chamber above said beam, tiers of tubes supported 50 on said tiers of bars, supports by means of which the said tiers of bars are supported, one above another, and independent of the tubes from said beam, an overhead beam 55 extending above the furnace roof, and a hanger supported from said overhead beam and extending downward through said roof and supporting the inside tube-supporting beam between its ends.

60 8. A furnace comprising walls and a roof enclosing a heating chamber, an overhead beam above the furnace roof, upper, lower and middle banks of tubes within the furnace, tiers of tube-supporting bars for each 65 bank of tubes, hangers depending from the

overhead beam and supporting the tiers of bars supporting the upper bank of tubes, beams extending transversely within the chamber between the middle and lower banks, means to support from one inside beam the tiers of bars supporting the middle bank of tubes, and means to suspend from the other inside beam the tiers of bars supporting the lower bank of tubes.

9. A furnace comprising walls and a roof 75 enclosing a heating chamber, upper, lower and middle banks of tubes within the furnace, tiers of bars supporting each bank of tubes, beams extending transversely within the chamber between the middle and lower bank of tubes, means to support from and above one inside beam the tiers of bars supporting the middle bank of tubes, means to suspend from and below the other inside beam the lower bank of tubes, overhead beams 80 above the furnace roof, and hangers supported from the overhead beams and supporting respectively the tiers of bars supporting the upper bank of the tubes and the two inside beams between their ends.

10. A furnace comprising walls and a roof 90 enclosing a heating chamber, a beam extending transversely within the chamber and through its side walls, tiers of tube-supporting bars extending transversely within the 95 chamber above said beam, supports by means of which the said tiers of bars are supported, one above another, from said beam, an overhead beam extending above the furnace roof, a hanger supported from said overhead beam 100 and extending downward through said roof and supporting the inside tube-supporting beam between its ends, and means, outside the chamber, supporting the ends of the inside tube-supporting beam.

In testimony of which invention, I have hereunto set my hand, at Marcus Hook, Pennsylvania, on this 27th day of July, 1928.

HENRY THOMAS.
